[57] CLAIM

The ornamental design for an “article pouch”, as shown and described.

DESCRIPTION

FIG. 1 is a front elevational view of an article pouch showing our new design, with the flap shown in a closed position.

FIG. 2 is a right side elevational view, with the flap shown in a closed position and with the left side elevational view being a mirror image thereof;

FIG. 3 is a rear elevational view;

FIG. 4 is a top plan view, with the flap shown in closed position;

FIG. 5 is a bottom plan view, with the flap shown in a closed position;

FIG. 6 is a front elevational view, with the flap shown in an open position;

FIG. 7 is a top plan view, with the flap shown in an open position;

FIG. 8 is a bottom plan view, with the flap shown in an open position;

FIG. 9 is a right side elevational view, with the flap shown in an open position, and with the left side elevational view being a mirror image thereof; and,

FIG. 10 is a front elevational view, with the flap shown in a closed position and in a position of use. The broken line showing of a person in FIG. 10 is for illustrative purposes only and forms no part of the claimed design.
